[57] CLAIM

The ornamental design for a scissors with hanger clip, as
shown and described.

DESCRIPTION

FIG. 1 is a rear elevational view of a scissors with hanger
clip showing my new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a rear elevational view of a second embodiment of
the design shown in FIG. 1, the only difference being the
placement of the hanger clip on the front of the scissors.
